UNITED STATES PATENT OFFICE.

JOSEPH STANFORD, OF PLUMERVILLE, ARKANSAS.

DESIGN FOR AN AX AND SAW-SET.

SPECIFICATION forming part of Design No. 34,941, dated August 13, 1901.

Application filed July 12, 1901. Serial No. 68,113. Term of patent 14 years.

To all whom it may concern:

Be it known that I, JOSEPH STANFORD, a citizen of the United States, residing at Plumerville, in the county of Conway and State of Arkansas, have invented and produced a certain new and original Design for an Ax and Saw-Set; and I do declare the following to be a full, clear, and exact description of the invention, such as will enable others skilled in the art to which it appertains to make and use the same.

The invention relates to a new and original design for an ax and saw-set; and it consists of the design shown in the accompanying drawings, in which—

Figure 1 is a perspective view, and Fig. 2 is a top plan view.

In the drawings, 1 denotes the blade, 2 the eye, and 3 the head. The upper surface of

the head is provided with a rectangular recess 4, which merges at one end into the plane of said surface and has an end wall 5 and side walls 6. The end wall 5 extends entirely across the head and is beveled, as shown at 7, while the side walls are horizontal from 8 to 9 and thence inclined downwardly from 9 to 10.

What I claim is—

The design for an ax and saw-set, as herein shown and described.

In testimony whereof I have hereunto set my hand in presence of two subscribing witnesses.

JOSEPH STANFORD.

Witnesses:

RILEY PARKER,
CLAUDE PARKER.
